US00D782243S

(12) **United States Design Patent** (10) Patent No.: **US D782,243 S**
(45) Date of Patent: **** Mar. 28, 2017**

(54) **FOOD CHOPPER**

- (71) Applicant: **McCormick & Company, Incorporated**, Sparks, MD (US)
- (72) Inventors: **Thomas Koll Porter Gieske**, Lutherville, MD (US); **Tracie L. C. Wilson**, Westminster, MD (US); **Olivier Rattin**, Althen Des Paluds (FR)
- (73) Assignee: **MCCORMICK & COMPANY, INCORPORATED**, Sparks, MD (US)
- (**) Term: **14 Years**
- (21) Appl. No.: **29/524,521**
- (22) Filed: **Apr. 21, 2015**

Related U.S. Application Data
